Primary Examiner — Bao-Yen T Nguyen*Assistant Examiner* — Loryn K. LeBlanc(74) *Attorney, Agent, or Firm* — Nitin Kaushik(57) **CLAIM**

The ornamental design for a softbox with tripod, as shown and described.

DESCRIPTION

FIG. 1 is a front perspective view of a softbox with tripod, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view shown in a folded state; and,

FIG. 10 is another rear perspective view shown separated for ease of understanding.

The broken lines in the drawings illustrate the portions of the softbox with tripod, which form no part of the claimed design.

1 Claim, 10 Drawing Sheets(56)
